UNITED STATES PATENT OFFICE

THOMAS HENRY JONES, OF WOODTHORPE, ENGLAND

KNITTED FABRIC AND THE PRODUCTION THEREOF

Application filed May 10, 1930, Serial No. 451,407, and in Great Britain May 11, 1929.

This invention comprises improvements in or relating to knitted fabrics and the production thereof, and has for its main object the production of a fabric in which the 5 tendency to or possibility of laddering, running or raveling is minimized or eliminated.

According to the present invention a fabric is provided composed of or embodying 10 knitted stitches wherein a lock or tie is formed by a thread bar extending between successively formed stitch loops and also constituting one of the intermeshing loops of a subsequently formed stitch.

In a knitted fabric composed of alternate 15 needle and sinker wales a bar of thread extending between successively formed stitch loops may in accordance with this invention be formed into a loop and threaded through a stitch loop located in one of the needle wales next alongside of the sinker wale from which said bar loop is drawn so as to constitute part of a locked or tied stitch in the said needle wale.

For the purpose of more fully describing 20 the nature of this invention reference will now be made to the accompanying drawings, wherein:—

Figure 1 illustrates a portion of plain 25 knitted fabric incorporating a locked or tied stitch in accordance with one embodiment of this invention.

Figure 2 shows a portion of fabric incorporating several of said stitches.

Figures 3 and 4 illustrate two methods of 30 forming a modified lock or tie in plain knitted fabric.

The term "bar" is used throughout the 35 specification as referring to the thread extending between two successively formed stitch loops. The phrases "loop" and "stitch" are given their normal significance.

One embodiment of the invention (Figures 1 and 2) will now be described as applied, by way of example, to what is customarily known as plain hosiery fabric.

Thread 1 constituting a sinker bar extending between or connecting two adjacent 40 stitches 2 on a horizontal course is taken in the form of a loop and passed through a stitch 3 in a subsequent course or row, con-

veniently the next course, the stitch 3 through which said loop is threaded being advantageously in the same vertical row or wale as that containing either of the two stitches 2 from between which the loop 1 is drawn. A stitch 4 of a further subsequent course is now caused to pass through the closed end of the aforesaid loop 1 subsequently to passing said loop through the first-named stitch 3, and the closed end of the loop 1 thus becomes a virtual additional stitch in the wale in which it is located, i. e. a normal needle stitch, while the stitch 3 which passes over or encircles the loop 1 constitutes a tie or knot on said loop which any tension or pull on the fabric will tend to tighten.

Groups of stitches with a knot or tie as above may be produced in succession, one group immediately following another, in which case the portion of the closed loop extending beyond the knot or tie may constitute the commencement of the next group. The knotted or tied stitches may, however, be spaced by any desired number or type of 55 stitches.

In Figures 3 and 4 the sinker bar loops 1 are each threaded through a stitch loop 2 appertaining to the same knitted course as that from which the bar loop 1 is drawn, in which case the loops 1 function as stitch loops in the course or row next succeeding that from which said loop is drawn. In Figure 3 the tied or locked stitches are in each needle wale, while in Figure 4 such stitches are produced in alternate needle wales, this being determined by the method of transferring the bar loops 1 to the needles.

In producing locked fabric as shown in any of the figures previously described the bar loops 1 which are drawn from between adjacent stitch loops are each retained on any suitable picker needle or equivalent retaining element while one or more subsequent courses are knitted upon the needles of the machine, after which the loop 1 which is retained by said picker, needle or its equivalent is transferred into the hook of an adjacent needle. Prior to said transference being effected, however, the stitch loop 3

previously existing on the shank of the needle is cleared and after said transference has been effected the said cleared stitch loop 3 is knocked over so that the bar loop 1 5 becomes in effect a new stitch loop while the cleared loop 3 which is knocked over encircles the loop 1 and forms a locking loop. The thread subsequently fed to the needles is then drawn through the transferred bar 10 loop 1 in the normal manner.

The transferring of the loop from the picker or the like to the needle may be accomplished by any known or approved transferring means. For example, the picker 15 may be displaced laterally or diagonally so as to cause the needle to rise within the loop carried thereby, or said transferring element may be so cranked or shaped as to shog the loop carried thereby laterally by longitudinal or endwise movement of said element.

In a further alternative arrangement one or more stitches may be formed on or by the thread constituting the sides of the drawn bar or sinker loop, the closed end of said 20 loop subsequently having a further stitch drawn therethrough.

I claim:—

1. A knitted fabric composed of alternate needle and sinker wales and wherein 30 a thread portion constituting a sinker bar is formed into a loop and threaded through a stitch loop located in one of the needle wales adjacent to the sinker wale from which said bar loop is drawn so as to constitute part of a locked or tied stitch in the 35 said needle wale.

2. A knitted fabric wherein a thread bar which extends between two successively-formed stitches in the same course appertaining to stitch wales located next alongside each other in the fabric is formed into a loop and passed through a stitch loop in a subsequently knitted course or row, a stitch loop in a further subsequently knitted 45 course or row being then passed through the closed end of the first-named bar loop, which loop thus becomes part of a locked or tied stitch.

3. A knitted fabric wherein a thread bar 50 loop taken from between successively formed stitches in a course or row of stitches is passed through a stitch loop appertaining to the knitted course or row from which said bar loop is taken, a stitch loop in a subsequently knitted course being then passed through the closed end of the said bar loop which loop thus becomes part of a 55 locked or tied stitch.

4. A knitted fabric wherein a thread bar 60 which extends between stitches in the same course located in stitch wales disposed next alongside each other in the fabric is drawn in the form of a stitch loop through a stitch loop formed in a subsequently knitted 65 row, said latter stitch loop being cast off to

surround the drawn thread bar loop and becomes part of a locked or tied stitch, said drawn bar loop forming in effect an additional stitch loop in the wale in which it is located.

5. A method of producing knitted fabric which consists in drawing a loop from a thread bar extending between stitch loops in a given course appertaining to needle wales located next alongside each other, 70 passing the said drawn loop through a stitch loop in one of said needle wales in a subsequently knitted course and casting-off said stitch loop so that the said drawn thread loop constitutes in effect an additional 75 stitch loop in the wale in which it is located.

6. A knitted fabric wherein a thread bar extending between and forming a connection between the stitch loops in two stitch wales located next alongside each other is 80 drawn in the form of a loop through a subsequently-formed stitch loop in one of said 85 wales, the latter loop being cast off around the extended bar loop to form a lock or tie thereon.
